UNITED STATES PATENT OFFICE.

RESSA C. WAGNER REINERT, OF KEOTA, IOWA.

BED.

SPECIFICATION forming part of Letters Patent No. 752,103, dated February 16, 1904.

Application filed April 9, 1903. Serial No. 151,882. (No model.)

To all whom it may concern:

Be it known that I, RESSA C. WAGNER REINERT, a citizen of the United States, residing at Keota, in the county of Keokuk and State of Iowa, have invented a new and useful Bed, of which the following is a specification.

This invention relates to certain improvements in beds, and more particularly to that class known as "metallic" beds.

The primary object of the invention is to provide a simple, inexpensive, and durable bed so constructed that the ends of the spread or outer covering may hang freely and gracefully in position, covering the foot-rail and giving the bed a handsome finish.

A secondary object of the invention is to provide a novel form of foot-piece adapted to prevent longitudinal movement of the mattress, thereby permitting the under covering to be tucked beneath the mattress and securely held from displacement and at the same time permitting the outer covering or spread to be draped thereover in any desired manner.

The invention consists in the construction and novel combination and arrangement of parts hereinafter fully described, illustrated in the accompanying drawings, and pointed out in the claim hereto appended, it being understood that various changes in form, proportion, and minor details of construction may be resorted to without departing from the spirit or sacrificing any of the advantages of the invention.

In the accompanying drawings, Figure 1 is a perspective view of a metallic bed constructed in accordance with my invention. Fig. 2 is a side elevation of the same. Fig. 3 is a front elevation of a modified form of foot-piece. Fig. 4 is a perspective view illustrating a further modification, and Fig. 5 is a top plan view of Fig. 4.

Similar numerals of reference indicate corresponding parts in all the figures of the drawings.

1 designates my improved bed; 2, the head and foot posts; 3, the side rails, and 4 the cross or end rails. Secured in any suitable manner to the lower ends of the foot-posts 2 or formed integral therewith are a pair of vertically-disposed arms 5, connected at the top

by cross-rails 6 and 7, constituting the foot-piece. The lower end of the arms 5 are each provided with an elbow 6', which space said arms a slight distance from the footboard, defining a passage therebetween to allow the spread or outer bed-covering to hang over the end of the mattress. Secured to the arms 5 in any suitable manner, as by welding, casting, or otherwise, and at points adjacent their free ends are dovetail socket members 7', adapted to receive corresponding tenons on the side rails 3, forming the frame of the bed, upon which the springs and mattress rest. The ends of the arms 5 extend vertically some distance beyond the side rails 3, forming a stop 65 and preventing the mattress from slipping longitudinally and obstructing the passage formed between the arms 5 and the footboard, and also permits the under covering to be tucked beneath the mattress and retained in 70 said position without the liability of being displaced, as clearly shown in Fig. 2 of the drawings.

In making up the bed the ends of the sheets or other under covering may be tucked beneath the mattress, being prevented from displacement by the foot-piece, the end of the spread or other drapery being passed over the cross-rails and dropped into the passage or recess formed between the foot-piece and the 80 footboard, where they hang gracefully, effectually covering and concealing the cross-rails and giving a neat tidy appearance to the bed.

In Fig. 3 I have shown a modified form of the invention in which the foot-piece is formed in two sections detachably secured together, the ends of the arms 5 being provided with sockets 8, adapted to receive the dowel-pins 9, formed on the upper section 10 and by means of which said sections are secured together.

In Fig. 4 I have shown a further modification of the foot-piece designed particularly for use in connection with bow-foot beds. In this case the arms 5 are dispensed with, the foot-piece being formed, as shown, of two parallel horizontally-disposed bars 10, connected in any suitable manner to the sides or uprights 11, the ends of said uprights being provided with bifurcated end portions 12, adapted to 100

engage the foot-posts just above the socket members.

From the foregoing description it will be seen that I have produced an exceedingly simple, inexpensive, and durable bed, the relative disposition of the several parts being such as to permit the spread or outer bed-covering to be freely and gracefully draped thereon and the under covering retained in position beneath the mattress, which is effectually prevented from moving longitudinally by reason of the foot-piece.

Having thus described the invention, what I claim, and desire to secure by Letters Patent, is—

In a bedstead, the combination of the head-board, footboard and side rails, upwardly-extending brackets secured to the lower portion of the footboard and spaced therefrom, and a foot-rail forming a part of the bed-frame 20 carried by the brackets and extended above the side rails to thereby prevent longitudinal movement of the mattress.

In testimony that I claim the foregoing as my own I have hereto affixed my signature in 25 the presence of two witnesses.

RESSA C. WAGNER REINERT.
